WINDOW SEAT

Abraham Reisner, New York, N. Y.

Application August 19, 1935, Serial No. 36,898

2 Claims. (Cl. 304—24)

This invention relates to window seats and more particularly to the brackets securing the seat to the window sill and the object of the invention is the securing of said brackets beneath the seat and providing them with hooks for the window frame at their inner ends while the outer ends have supports to hold the seat above the outer sill.

A further object of the invention is to provide the seat with a screw clamp that engages the outer edge of the frame sill to cooperate with the hooks to secure the seat to the window sill.

These and other objects and details of the invention are more fully described in the following specification, set forth in the claims and illustrated in the accompanying drawing, wherein:

Figure 1 is a perspective view of the lower part of a window frame showing a seat secured to the sill by the improved brackets.

Fig. 2 is a cross sectional view of a window sill with the improved seat applied thereto.

Fig. 3 is a perspective view of the clamp detached.

Fig. 4 is a perspective view of a bracket.

The improved window seat is adapted for use by window cleaners who require a position on the outer side of the window sash for cleaning or otherwise needing access to same.

The seat 11 may have back support of sheet metal or be appropriately constructed by other means and has the wood base 12. The brackets 13 are identical and are of metal having each a hook 13^a at its inner end and a rectangular support 13^b to hold the seat a desired distance above the sill of the brick work 18. The hook 13^a may be of appropriate shape to fit the molding 17 of

the frame sill while the support 13^b may consist of a loop of the metal where it is turned back on itself and one of the screws 19 uniting the metal parts and securing the bracket to the base 12 and for which purpose another screw 19 passes through the bracket and into the base near its front end. As shown in the drawing the brackets 13 are preferably of strip steel.

Depending from the base 12 between the two brackets 13 is a bracket 14 in which is journaled the clamping screw 15 carrying at its inner end the clamping member 16 having spurs to engage the frame sill 17 on its outer edge. The bracket 14 is preferably secured to the base 12 by the screws 19.

It is obvious that the parts of the device may be otherwise arranged or modified without departing from the essential features above described or from the scope of the appended claims.

What I claim as new is:

1. In window seats, the combination with a seat, strap-iron brackets each having a hook at its inner end and a support for the seat at its outer end, a bearing bracket depending from the seat between the supports, and a clamping screw in the bearing bracket.

2. In window seats, the combination of a seat, strap iron brackets each secured to the bottom of the seat at each side and formed with loops to support the said seat at their outer ends and with hooks at their inner ends to engage the window sill, a bearing bracket secured to the said seat between the strap iron brackets, and a clamping screw playing in the bearing bracket and carrying spurs at one end.

ABRAHAM REISNER.
